UNITED STATES PATENT OFFICE.

W. A. REX, OF NEWVILLE, INDIANA.

IMPROVED PUNCH.

Specification forming part of Letters Patent No. 59,453, dated November 6, 1866.

To all whom it may concern:

Be it known that I, W. A. REX, of Newville, in the county of De Kalb and State of Indiana, have invented a new and useful Improvement in Punches; and I do hereby declare that the following is a full, clear, and exact description thereof, which will enable others skilled in the art to make and use the same, reference being had to the accompanying drawings, forming a part of this specification, in which—

Figure 1 is a side view of a punch with my improvement attached. Fig. 2 is a detail sectional view of the same, taken through the line $x x$, Fig. 1. Fig. 3 is a side view of one of the cutter-tubes detached from the stock.

Similar letters of reference indicate like parts.

My invention has for its object to furnish an improved means by which the cutter-tubes may be readily and quickly attached to and removed from the stock, and securely held therein while the tool is being used; and it consists of the combination of a spring-catch and removable cutter tube or tubes with each other and with the punch-stock, as hereinafter more fully described.

A is the punch-stock, the parts or halves of which are constructed and pivoted to each other in the ordinary manner.

Through one of the jaws, a' , of the stock A is formed a square hole for the reception of the shank b' of the cutter-tubes B. In the side of the jaw a' is formed a groove, leading back from the square hole before described, for the reception of the spring-catch C, as shown in Figs. 1 and 2. The rear part of this groove is deepened for the reception of the spring c' ,

which holds the catch C closed by pressing against the under side of its rear end, as shown in Fig. 2.

The catch C is pivoted within the groove in which it works by a pin, c^2 , as shown, and has a projection formed upon the under side of its forward end, which enters a notch formed in the square shank b' of the cutter-tubes B for its reception.

The lower or cutting part of the cutter-tubes B is made in the usual form and manner; but the upper parts or shanks, b' , of all the various sizes are made of the same size and square, so that they may all fit into the same square hole formed in the jaw a' of the stock A, as before described.

In one of the side edges of the shank b' of the cutter-tubes B is formed a notch for the reception of the projection formed upon the catch C, as before described.

By pressing upon the rear end of the catch C its forward end is lifted away from the shank b' of the cutter-tube B, allowing said cutter-tube to be removed and replaced with another of the desired size.

I claim as new and desire to secure by Letters Patent—

The combination of the spring-catch C and removable cutter tube or tubes B with each other and with the punch-stock A, when the said parts are constructed and arranged substantially as herein shown and described, and for the purpose set forth.

W. A. REX.
